US0D1067878S

(12) **United States Design Patent** (10) **Patent No.:** **US D1,067,878 S**
(45) **Date of Patent:** **** Mar. 25, 2025**

(54) **BATTERY ADAPTER**

(71) Applicant: **Cheng Luo**, Hengyang (CN)

(72) Inventor: **Cheng Luo**, Hengyang (CN)

(**) Term: **15 Years**

(21) Appl. No.: **29/927,386**

(22) Filed: **Feb. 5, 2024**

(30) **Foreign Application Priority Data**

Jan. 22, 2024 (CN) 202430042493.X

(51) **LOC (15) Cl.** **13-02**

(52) **U.S. Cl.**

USPC **D13/103**

(57) **CLAIM**

The ornamental design for a battery adapter, as shown and described.

DESCRIPTION

FIG. 1 is a top perspective view of a battery adapter, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of area 8 in FIG. 1; and, FIG. 9 is an enlarged detail view of area 9 in FIG. 1.

The dash-dash broken lines in the drawings illustrate the portions of the battery adapter, which form no part of the claimed design.

The dash-dot-dash broken lines encircling the enlarged views are for annotative purposes only and form no part of the claim thereof.

1 Claim, 9 Drawing Sheets
